UNITED STATES PATENT OFFICE

JOHN KREMER, OF WEST ORANGE, NEW JERSEY, ASSIGNOR TO CHARLES ENGELHARD, INC., OF NEWARK, NEW JERSEY, A CORPORATION OF NEW JERSEY

ELECTRICAL CONTROL DEVICE

Application filed November 27, 1929. Serial No. 410,066.

This invention relates to electrical control devices, and more particularly to automatic control and indicating instruments adapted for use in connection with heat generating apparatus.

In instruments of the type herein considered there are generally employed two or more switches for the purpose of closing an electrical circuit and for opening the circuit when a predetermined maximum condition has been reached.

Heretofore, the circuit controlling switch has been directly or indirectly actuated by an intermittently oscillating depressor bar.

The circuit opening switch is usually actuated by the depressor bar bearing upon the indicating pointer of the instrument, the pointer in turn closing the switch, the latter being so positioned that the pointer will be effective only when a maximum condition has been attained.

Obviously, in order to insure proper operation and prevent actuation of the opening and closing switches at an improper time, that is, before the maximum has been reached, it is necessary that the depressor bar be accurately adjusted; in many instances, these adjustments being in the neighborhood of .002 of an inch.

It is an object of this invention to provide an arrangement of switches in a control instrument by which the circuit closing switch is periodically actuated independently of the movements of the depressor bar.

A further object is the provision of a control device in which a circuit opening switch is actuated for a predetermined time before and after the actuation of circuit closing switch when a maximum condition has been reached.

These and other objects are attained by the novel construction, combination and arrangement of parts hereinafter described and shown in the accompanying drawings, constituting a material part of this disclosure and in which:

Figure 1 represents an elevational view of an indicating instrument embodying the invention.

Figure 2 is a bottom view of the instrument shown in Figure 1.

Figure 3 represents a sectional view taken on the line 3—3 of Figure 2.

Figure 4 represents an inverted side view of a section of the instrument.

Figure 5 represents a diagram illustrating the relative periods of closing of switches employed in the instrument.

Referring to Figure 2, the instrument is shown to include a main frame 6, upon which is supported a horse shoe magnet 7, of a galvanometer. The frame has attached thereto an arcuate cross-bar 8, which supports a scale 9. The instrument is carried in a casing 10, having a detachable cover 11, the latter being provided with a glass window 12 to enable the scale to be visible.

Rotatably mounted on a shaft 13 depending from the frame 6, is an arm 14, supporting a vertical bar 15, upon which is carried a horizontal shelf 16, having mounted thereon a pair of contacts 17 and 18, Figure 1, adapted to be engaged by contacts 17' and 18' attached to plates 19 and 20, respectively, said plates being supported by the shelf 16, and normally held in an elevated position by leaf springs 21. (Fig. 4).

A pointer 22, connected with the movable element of the galvanometer, traverses the scale 9, and has attached thereto a lug 22' for the purpose hereinafter described.

A substantially U-shaped depressor bar 23 is positioned above the pointer and the plates 19 and 20, the depressor bar being pivotally mounted to the frame 6 at 24, Fig. 4, and is normally urged downward by a tension spring 25.

One leg of the bar 23 has a downwardly bent portion 26 carrying a roller 27, the latter engaging the cam surface 28 of a disc 29 fixed to a shaft 30 which is connected to a small electric motor 32, Figures 1 and 2, having a predetermined speed.

Also fixed to shaft 30 is a disc 33 having a peripheral lug 34 adapted to periodically engage the leaf spring 35 upon which is carried a contact 36 adapted to engage a similar contact 37 carried by a leaf spring 38, the springs 35 and 38 being attached to and sep-

arated by a block 39 of insulating material. The block 39 is mounted on a projection 40 from a sheet metal bracket 41, upon which is supported the motor 32 and its associated parts.

In operation, the lug 34 on disc 33 causes periodic engagement of contacts 36 and 37, which establishes a circuit through apparatus designed to cause heat to be generated in a furnace. At the same time, the rotation of disc 29 causes the depressor bar 23 to be intermittently raised and lowered.

As the heat in the furnace increases, the galvanometer is affected and needle 22 traverses the scale 9 until it is above either plate 19 or 20, at which position depressor bar 23 bears down on the needle, and the lug 22' on the needle bears down on the plate to cause contacts 17 and 17' or contacts 18 and 18' to be engaged to close a circuit through apparatus designed to continue or discontinue the generation of heat in the furnace.

Cam 28 is so designed and positioned relative to lug 34 that the flow of heat will be discontinued 18° before the contacts 36 and 37 are brought into engagement and 18° afterwards.

The contacts 36 and 37 remain engaged for a period of 12° , so that the cam 28 embraces an arc of 48° , the apparatus for discontinuing the flow of heat being in operation throughout that period. This arrangement eliminates the possibility of faulty operation of the control instrument, and as soon as the furnace heat has decreased to an extent sufficient to cause the pointer to clear the plates 19 and 20, the heat generating apparatus will again be placed in operation by the engagement of contacts 36 and 37.

The switch control arrangement herein described necessitates the actuation of only one switch by the pointer and the depressor bar; and since the heat generating switch is entirely independent of the pointer or the position of the pointer, or the setting of the cut-off switches, it may be made mechanically stronger than has heretofore been possible.

This feature is of great advantage, especially in view of the fact that in depressor bar actuated switches very close adjustment of the depressor bar is necessary, such adjustments in many instances being in the neighborhood of .002 of an inch, in order to avoid making contact with a heat generating switch and a cut-off switch simultaneously at an improper time.

The foregoing disclosure is to be regarded as descriptive and illustrative only, and not as restrictive or limitative of the invention, of which, obviously, an embodiment may be constructed including modifications without departing from the general scope herein indicated and denoted in the appended claim.

Having thus described my invention what

I claim as new and desire to secure by Letters Patent is:

In a control instrument, a shaft, means for rotating the shaft at a predetermined speed, a pair of leaf springs attached to and separated by a block of insulating material, said leaf springs carrying contacts, said contacts being normally spaced apart, a disc fixed to the shaft and having a peripheral lug periodically engageable with one of the leaf springs to force the contacts into engagement, a depressor bar pivotally supported intermediate of its ends, said depressor bar having a downturned portion at one side of the pivot and a transverse portion at the opposite side of the pivot, a cam disc fixed to the shaft adjacent the first mentioned disc and engaging the downturned portion of the depressor bar to intermittently actuate the latter, a normally open switch positioned beneath the transverse portion of the depressor bar, and a meter pointer movable above said switch and cooperating with the depressor bar to close the switch when the pointer is in a predetermined position, said cam disc being so shaped and arranged relative to the first mentioned disc as to maintain the depressor bar depressed for a definite time before and after the engagement and disengagement of the contacts on the leaf springs.

This specification signed this 22nd day of November, 1929.

JOHN KREMER.
